UNITED STATES PATENT OFFICE.

ROBERT MAURICE BIDELMAN, OF ADRIAN, MICHIGAN, ASSIGNOR TO THE PETROLEUM LIGHT AND HEAT COMPANY, OF SAME PLACE.

PROCESS OF CARBURETING AIR.

SPECIFICATION forming part of Letters Patent No. 377,735, dated February 14, 1888.

Application filed April 21, 1887. Serial No. 235,605. (No model.)

To all whom it may concern:

Be it known that I, ROBERT MAURICE BIDELMAN, of Adrian, in the county of Lenawee and State of Michigan, have invented new and 5 useful Improvements in Processes of Carbureting Air; and I do hereby declare that the following is a full, clear, and exact description thereof, reference being had to the accompanying drawing, which forms a part of this 10 specification.

This invention relates to certain new and useful improvements in a process for the manufacture of illuminating oil-gas and the apparatus for carrying out such process. In the 15 manufacture of such gas by carbureting air with the vapors of crude or unrefined hydrocarbon oils it is necessary that such manufacture should be nearly simultaneous with its use, as the tendency of such gas is to 20 become dense at certain temperatures, so that it cannot be stored for future use with economy, for condensation not only takes place in the holder, but also in the service-pipes.

The object of the present invention is to so 25 manufacture such gas that it will not condense under ordinary circumstances, but become practically a fixed gas.

The invention consists in so treating the air 30 in its passage through the carburetor that the heavier vapors of the hydrocarbons employed 35 will not be carried off with the more volatile vapors, and that the gas thus made is passed through a washer containing strong soapsuds, the alkali in which has an affinity for the fatty 40 constituents of crude oils, and will take them up, and thereby remove those portions that tend to condensation, letting a fixed vapor pass to the holder, where it may be stored until required for consumption.

45 In order to better understand this process, reference is had to the accompanying drawing, which forms a part of this specification, and which shows a longitudinal sectional view of a preferred form of apparatus, and wherein A represents a fan or blower for forcing the air through the carburetors B by the pipe C, leading into the carburetor nearest the blower. The carburetors are set in series, as shown, and so arranged with dividing-diaphragms D 50 that the air entering under pressure at the top

of the first compartment is compelled to pass under the diaphragm and rise in the next compartment, passing out at the top thereof into the next carburetor at its top, thence downward and under the diaphragm in this 55 compartment, and rising in the next, to pass out at its top, and so on until the gas is conveyed from the last compartment to the holder E through the pipe F. These carburetors may consist of a long box divided in pairs of 60 compartments by means of partition-walls G, extending from the bottom nearly to the top, with intermediate diaphragm, D, pendent from the top of the air-tight box nearly to its bottom, in order to give the zigzag direction 65 to the air currents described.

There are several of these chambers employed, each being divided into two compartments by means of the hanging diaphragms D. Each of these chambers is filled with charcoal 7c and the charcoal saturated with any suitable hydrocarbon containing some of the lighter volatile oils. The air being forced through, as described, takes up any of the volatile vapors—preferably the more volatile ones—and 75 also a certain amount of the tarry matters present in the oil.

From the first carburetor the gas is passed through soapsuds, which act in two ways, first mechanically in washing the gas—that is, 80 freeing it of the heavier vapors, whose tendency to be readily condensed is greatly increased by the physical properties of the soapsuds, as well as by the hydrostatic pressure it has to undergo in passing through—and, secondly, in a chemical way by absorbing the 85 tarry matters.

The gas escaping from the soapsuds has been deprived of a portion of its vapors—namely, the heavier ones—and in its passage 90 through the next carbureting-chamber it will again be in a condition to take up some more vapor, but this time a much smaller amount, and consequently a less amount of heavy vapors than in the first carburetor. By a repeated process of washing, as before, the heavy 95 vapors are again abstracted, and the gas resulting may be now directed into the holder, or passed through more carbureting and washing chambers, if thought necessary.

I use charcoal in the carburetors, as it presents a large amount of surface, permits the air to pass readily through it with the pressure of a fan-blower, and further prevents the 5 mechanical abstraction of oil by the blast and absorbs a relatively large quantity of oil.

The soapsuds I prefer to other alkaline solutions on account of their chemical and physical properties.

70 From the nature of the process it will be understood that the washing and carbureting chambers may be multiplied to any extent desired.

What I claim as new is—

The process of manufacturing illuminating 15 oil-gas herein described, consisting of a series of like operations, each operation comprising two separate steps, the first consisting in forcing the air through a carbureting chamber filled with charcoal saturated with hydrocarbon, and the second in forcing the air through soapsuds, substantially as described.

ROBERT MAURICE BIDELMAN.
